UNITED STATES PATENT OFFICE.

THOMAS A. NELSON AND JOHN MURRAY, OF EDINBURGH, SCOTLAND.

PRINTING AND SIMILAR MACHINERY.

No. 807,191.

Specification of Letters Patent.

Patented Dec. 12, 1905.

Application filed July 15, 1905. Serial No. 269,775.

To all whom it may concern:

Be it known that we, THOMAS ARTHUR NELSON, of the firm of Thomas Nelson & Sons, printers and publishers, and JOHN MURRAY, engineer, subjects of the King of Great Britain, and residents of Parkside Works, Dalkeith Road, Edinburgh, Scotland, have invented new and useful Improvements Relating to Printing and Similar Machinery, 5 of which the following is a specification.

The present invention has for its object the more correct adjustment or register of sheets of paper or other material when being fed into printing, folding, or other similar 15 machines.

In machines to which this improvement applies there is a feeding-table, and there are front-lay guides, and there is also an end lay or side lay, with a gripper or jaws capable of 20 being opened and closed. In the said machines as they are operated at present a sheet of paper or other material is placed on the feeding-table with its front edge in contact with the front-lay guides. The end lay 25 advances laterally across the feeding-table with its gripper open and pushes the sheet in front of it a short distance across the feeding-table. The gripper of the end lay then closes on the edge of the sheet, and the end 30 lay retires, drawing the sheet after it into the home position. The front-lay guides are then removed simultaneously, and the end-lay gripper releases the sheet, which is then ready to advance into the machine.

According to this invention the parts of 35 the mechanism are the same; but in order to insure a better register of the sheets the parts are differently operated in the following manner: When the end-lay gripper has 40 closed on the edge of the sheet, but before it has begun to move backward into the home position, the front-lay guide which is nearer to the end lay is removed from contact with the front edge of the sheet. As the end lay 45 retires into the home position the front edge of the sheet is then resting against one front-lay guide only. When the end lay reaches the home position, the remaining front-lay guide is withdrawn from contact with the 50 edge of the sheet, and the end-lay gripper releases its hold in the usual way, and the sheet is then ready to advance into the machine.

The present improvements are illustrated in the accompanying drawings, whereof— 55

Figure 1 is a plan view, and Fig. 2 a front elevation, Fig. 3 being a side elevation of the cam for operating the front lays.

a is a feeding-table, (shown only in Fig. 1,) and *b* is a sheet placed thereon. 60

c is the end lay and gripper, which does not differ in construction and arrangement from the end or side lays usually employed.

d and *d'* are the front lays carried by the rocking shaft *e e'*, which is divided transversely within the sleeve *f*. The portion *e* of the rocking shaft is pinned fast to the sleeve *f*, and the portion *e'* is also pinned to it, but loosely, so that the portion *e* and sleeve can rotate to a limited extent without 70 turning the portion *e'*. The shaft is rocked by means of the arm *g*, carrying the bowl *h*, which bowl rides on the edge of the cam *i*. The cam *i* has two lifts 1 2 and 2 3 4. 1 2 rocks the shaft *e* sufficiently to raise the 75 front lay *d*. The lift 2 3 4 of the cam, however, rocks still further the portion *e* and sleeve *f*, by which means the portion *e'* is also rocked, so that the lay *d'* is thereby raised.

j and *k* are springs for bringing the shaft 80 *e e'* and lays *d d'* back to their normal position.

The operation of the mechanism is as follows: A sheet *b* having been placed on the feeding-table in contact with the front lays, 85 the end lay *c* is moved forward with open jaws and pushes the sheet from the dotted position to the drawn position shown. The jaws then close in the ordinary manner on the sheet; but before the latter is drawn 90 back the front lay *d* is raised by the cam, as above explained. The backward movement of the lay *c* then takes place, and the sheet is drawn into the home position with its edge in contact with the lay *d'* only. When the 95 sheet is at rest, the lay *d'* is also raised, and the sheet is ready to proceed onward to the printing or other machine.

It will be found that the use of one front lay only when drawing the sheet into the 100 home position greatly facilitates accurate register. The ordinary adjustments of the lays are provided.

What we claim, and desire to secure by Letters Patent of the United States, is— 105
In printing and similar machinery means

whereby an improved register of the sheets is effected, such means comprising mechanism for removing the front lays one before the other, mechanism for moving the sheet 5 back and forth, and means for so timing the movements that one lay is removed before and one after the sheet is moved into the home position, substantially as set forth.

In testimony whereof we have signed our names to this specification in the presence of 10 two subscribing witnesses.

THOMAS A. NELSON.
JOHN MURRAY.
